Atty's.

UNITED STATES PATENT OFFICE.

CHARLES A. PIERSON, OF SHARON, PENNSYLVANIA.

TRACK ALIGNING AND SPIKING DEVICE.

Application filed October 18, 1923. Serial No. 669,419.

To all whom it may concern:

Be it known that I, CHARLES A. PIERSON, a citizen of the United States, and resident of Sharon, in the county of Mercer and 5 State of Pennsylvania, have invented certain new and useful Improvements in Track Aligning and Spiking Devices, of which the following is a specification.

My invention relates to a device for assisting in the aligning and laying of railroad track.

The principal object of this invention is the provision of simply constructed means which will enable a track man to secure a purchase on the ballast with a crow bar, or 15 the like instrument, when a track is being aligned or moved from one location to another, the same device being used to lift a rail tie against the track while the parts 20 are being spiked together.

Another and important object of the invention is the provision of means as above which will be so constructed as to prevent 25 backward movement of itself under action of the crow bar when moving the rail.

The preferred embodiment of my invention is illustrated in the accompanying drawing, which is merely the best form of which I am now aware, and in these drawings:

Figure 1 is a top plan view of my device.

Fig. 2 is a sectional elevation on the line 2—2 of Fig. 1.

Fig. 3 is a bottom plan, and

Fig. 4 is an end elevation.

Referring now to the illustrative example, I have shown a plate 1 provided with a substantially semi-circular fulcrum 2 and other projections 3, the latter projections being 40 situated near the extreme edges of the plate 1 so as to leave a gap between themselves. A cut-away portion or trough 4 is provided in proximity to the fulcrum 2 and one edge 45 of the plate 1. On the reverse side I provide a series of lateral projections 5. It will be understood that these various projections and the fulcrum, may be of any desired configuration and may be made integral with the plate, as by casting the device, or may be applied separately, as will 50 be found expeditious. In operation when it is desired to move the track from one location to another, as in aligning the device will be placed with the fulcrum side down and at a point between ties and between rails, or slightly nearer the rail upon

which the operator will apply direct force from the crow bar. If the crow bar is then inserted beneath the rail and between ties from the outside of the track, the end of the 60 crow bar may rest between any of the projections 5 and as the entire device is prevented from moving backward or towards the operator by reason of the fulcrum 2 and the projections 3 sinking into the ballast, 65 the track can be moved by exerting sufficient upward force on the operator end of the crow bar. This operation is repeated as often as desired and the device may be shifted or adjusted as necessary. It will be 70 apparent that the surface of the device is sufficient to prevent the end of the crow bar which bears the entire weight of the track, from sinking into the ballast, and allows the same a positive purchase, while at the 75 same time the projections upon the under surface prevent backward slippage of the device as a whole.

When spiking rails to ties, which is usually done when the ties are not in ballast, 80 it is necessary that the tie be raised and held against the base of the rail while the spiking operation is carried out. In utilizing this device to aid in spiking rails and ties together, it is simply necessary to turn the 85 device over on the other side with the projections 5 down, placing the device in line with the tie being spiked and near the end thereof. If now the operator places a crow bar upon the fulcrum 2 projecting downwardly against the bottom of the trough 4 and beneath the end of the tie, he may, by exerting downward force on his end of the crow bar, lift the tie to the desired extent 90 against the rail. The fact that the projections 3 are separated will allow the operator's end of the crow bar to be brought down between them, or until the end of the bar touches the ground.

It will now be apparent that this combined device has distinct advantages in each 100 of its uses, and that the projections useful for one purpose on one side, are equally useful for another purpose when the device is reversed.

Having thus described my invention, what I claim is:

1. A device for assisting in moving a track and spiking rails and ties together, which includes a plate, the plate having at one end 110 a cut-away trough.
2. The device of claim 1, projections there-

on, said projections including a series of lateral protuberances one of which is capable of serving as a fulcrum extending the entire width of the plate.

5. 3. A device of the character described, including a plate, a cut-away trough at one end thereof, a substantially semi-circular projection fulcrum adjacent said trough, two projections at the end of the plate opposite the trough separated so as not to inter-

fer with a downward movement of the end of a crow bar resting upon the fulcrum, the reverse side of said plate being provided with a plurality of parallel projections extending the entire width of the plate, said 15 projections and fulcrum being integral with said plate.

In testimony whereof, I affix my signature.

CHARLES A. PIERSON.
